P. Kingston Post

UNITED STATES PATENT OFFICE.

PETER KINGSTON POST, OF NEW YORK, N. Y.

DESIGN FOR A SYMBOLIC TIMEPIECE-DIAL.

54,180.

Specification for Design.

Patented Nov. 11, 1919.

Application filed June 11, 1919. Serial No. 303,489. Term of patent 14 years.

To all whom it may concern:

Be it known that I, PETER KINGSTON POST, a citizen of the United States, residing at New York, in the county of Kings and State of New York, have invented a new, original, and ornamental Design for a Symbolic Timepiece-Dial, of which the following is a specification, reference being had to

the accompanying drawing, forming part thereof.

The figure is a plan view of a symbolic timepiece dial, showing my new design.

I claim:

The new and ornamental design for a symbolic timepiece dial, as shown.

PETER KINGSTON POST.
